UNITED STATES PATENT OFFICE.

WILLIAM H. EDSALL AND HENRY EDWARD CHASE, OF WALLINGFORD, CONNECTICUT,
ASSIGNORS TO THE H. L. JUDD COMPANY, OF NEW YORK, N. Y., A CORPORATION OF
NEW YORK.

CURTAIN-ROD.

1,220,158.

Specification of Letters Patent. Patented Mar. 20, 1917.

Application filed October 5, 1916. Serial No. 123,816.

To all whom it may concern:

Be it known that we, WILLIAM H. EDSALL and HENRY EDWARD CHASE, citizens of the United States of America, residing at 5 Wallingford, Connecticut, have invented a new and useful Curtain-Rod, of which the following is a specification.

Our invention relates to an improved curtain rod and bracket construction, the object being to provide in such a device features of construction whereby a curtain rod may be easily applied to or removed from its bracket supports, and whereby when said rod is in place it will be securely held against accidental displacement or detachment. The 10 device also embodies various other features of advantages that will be apparent to the mechanic skilled in the art from a reading of the following description and an examination of the accompanying drawings.

In the drawings:

Figure 1 is a plan view partly in section of our rod and bracket, the former being broken away at the center.

Fig. 2 shows an end and a side elevation of the bracket.

Fig. 3 is a view of the inside of one end of the rod with the bracket shown in section, the parts being assembled in their 30 operative position.

Fig. 4 illustrates a modification.

1—2 represent two telescopic sections of a curtain rod, said rod being preferably made telescopic so as to be adjustable to window or door passages of different widths. The rod in cross section in its preferred form is substantially flat with the two edges turned in toward each other but preferably not meeting. 3—3 represent parts of a window casing to which the rod is to be secured. The rod is secured thereto through the medium of brackets. The brackets each comprise an outwardly extending arm 4 which may be secured to the window casing in any desired manner. In this instance, each bracket 40 includes a base or foot 5 which may be provided with one or more screw holes so that the bracket may be secured to the casing by means of screws 6—6. 7 is a stud or a mechanically equivalent device at the inner side 45 of the arm 4 which is adapted to pass through a key-hole slot 8 in the side of the curtain rod. 9—9 are guides for steadyng the ends of the rod when the latter is in its 50 operative position, as shown in Fig. 3.

These guides may be formed in any suitable way but are preferably formed by bent over ears at the upper and lower edge of the arm 4. These guides are obviously located at different distances from the base 5 of the bracket than the stud 7, and hence coöperate with the stud in supporting the rod in its operative position. In this particular instance, the guides 9—9 are between the base 5 and the stud 7, which construction is preferred. Any suitable means may be provided to secure a friction fastening for the rod and bracket to hold the latter in its operative position. In the present instance we may provide a detent 10 in the side of each arm 4 which snaps into the enlarged end of the key-hole slot 8 when the rod is in its home position, as shown in Figs. 1 and 3. In applying the rod each end of the rod is first slipped over the stud of its respective bracket, the end of the rod clearing the guides 9—9 at such a time. The rod is then swung into the plane indicated in the horizontal dotted lines shown in Fig. 2 and then pushed rearwardly so as to force the 70 end of the rod between the guide ears 9—9 and so as to bring the larger end of the key-hole slot into position to clear the detent 10, which detent snaps into the slot as best seen in the right hand sectional portion of Fig. 1, 75 in which position said detent serves to prevent the outward movement of the rod unless sufficient force is applied thereto to effect an intentional disconnection of the parts. Obviously, the brackets are adapted 80 for either right or left hand use thus making it impossible to err in the assembling or setting up of the device.

It will be appreciated that we have shown our invention as to its various details of construction only in its preferred form, and that various modifications may be made as to said features without departing from the spirit and scope of the invention.

For example, in Fig. 4, we have shown the 100 detent 10^a formed by slitting the plate 4 so as to form a spring tongue having a hump near its free end.

Our present construction makes it a comparatively easy matter to attach the rod, the 105 first act is to hitch one end of the rod to the stud 7 allowing the rod to hang in the position shown in vertical dotted lines of Fig. 2. The rod is then adjusted so that the other end may be similarly hooked over the stud 110

of the other bracket, the head of the stud on the first bracket preventing the disengagement of the end first applied. The operator then swings the rod bodily into the horizontal position and pushes both ends rearwardly into the final operative position where they are engaged by the guides.

What we claim is:

1. In a bracket for a curtain rod comprising an outwardly projecting member, a stud projecting laterally therefrom near one end thereof, a guide near the other end, a rod having a slot adapted to slip over said stud by a lateral movement thereof and to be engaged with said guide by a longitudinal movement thereof.
2. In a bracket for a curtain rod comprising an outwardly projecting member, a stud projecting laterally therefrom near one end thereof, a guide near the other end, a rod having a slot adapted to slip over said stud by a lateral movement thereof and to be engaged with said guide by a longitudinal movement thereof, and means for frictionally holding said rod from accidental disengagement from said guide when the parts are assembled.
3. In a device of the character described, a curtain rod having a slot in its side near one end, a bracket including a plate, a headed stud on said plate near the outer end thereof, a guide on said plate toward the rear end thereof, one part of said slot being sufficiently large to pass over the head of said stud whereby said rod may be engaged therewith, a portion of said slot extending outwardly from said enlarged portion whereby said rod may be pushed rearwardly into engagement with said guide.

4. In a device of the character described, a curtain rod having a slot in its side near one end, a bracket including a plate, a headed stud on said plate near the outer end thereof, a guide on said plate toward the rear end thereof, one part of said slot being sufficiently large to pass over the head of said stud whereby said rod may be engaged therewith, a portion of said slot extending outwardly from said enlarged portion whereby said rod may be pushed rearwardly into engagement with said guide, said guide being constructed to prevent movement of said rod excepting in one direction.

5. In a curtain rod and bracket, a rod having a key-hole slot near one end thereof, the larger part of said slot being nearest the end, a bracket comprising a plate, a headed stud projecting laterally from said plate near the outer end thereof, a guide on said plate nearer to the rear end thereof than said stud, said guide being constructed to embrace the upper and lower side of said rod when the latter is in its operative position.

6. In a curtain rod and bracket, a rod having a key-hole slot near one end thereof, the larger part of said slot being nearest the end, a bracket comprising a plate, a headed stud projecting laterally from said plate near the outer end thereof, a guide on said plate nearer to the rear end thereof than said stud, said guide being constructed to embrace the upper and lower side of said rod when the latter is in its operative position, and means to hold said rod against accidental disengagement from said guide.

WILLIAM H. EDSALL.
HENRY EDWARD CHASE.
